UNITED STATES PATENT OFFICE.

FREDERICK E. GROUT, OF ORANGE, MASSACHUSETTS.

HYDROCARBON-BURNER.

SPECIFICATION forming part of Letters Patent No. 784,787, dated March 14, 1905.

Application filed July 14, 1904. Serial No. 216,484.

To all whom it may concern:

Be it known that I, FREDERICK E. GROUT, a citizen of the United States, and a resident of Orange, county of Franklin, State of Massachusetts, have invented an Improvement in Hydrocarbon-Burners, of which the following description, in connection with the accompanying drawings, is a specification, like figures on the drawings representing like parts.

10 This invention relates to hydrocarbon-burners, and has been especially designed as a burner for automobiles, which burner can be used for either kerosene, gasoline, or any other similar fuel.

15 One feature of the invention relates to a novel construction by means of which the air is delivered to the flame in such a way as to get the best possible combustion; and another feature of the invention relates to novel means

20 for controlling the supply of liquid fuel to the vaporizing-coil and the vaporized fuel to the burner-openings, whereby when the supply of liquid fuel to the vaporizing-coil is reduced to a minimum the vapor is delivered to a minimum number of burner-openings, the number being just sufficient to keep up steam in the boiler.

25 Other features of my invention will be more fully hereinafter described and then pointed out in the claims.

30 Figure 1 is a top plan view of my improved burner. Fig. 2 is a section on the line *xx*, Fig. 1. Fig. 3 is a top plan view showing the vaporizing-coil removed. Fig. 4 is a section 35 on the line *yy*, Fig. 1; and Fig. 5 is a section on the line *aa*, Fig. 3. Fig. 6 is a section on the line *bb*, Fig. 3; and Fig. 7 shows the "leaking-valve."

35 The burner comprises a burner-plate 3, which forms the top of a vapor-chamber 4, into which chamber the vaporized fuel is delivered, as will be presently described. In this form of my burner the burner-plate 3 is cylindrical and is surrounded by a suitable 40 flange 5, on which the boiler proper rests. The shape of the burner-plate and flange, however, may be varied without departing from the invention. Said burner-plate is provided with a plurality of corrugations which pref- 45 erably extend parallel to each other, and in

the ridge 7 of each corrugation are formed a plurality of burner-openings 6, preferably in the form of slits. The central rib 8 is shown as a larger size than the other ribs, and it has therein burner-openings 9 in the form of slits, 55 which, it will be seen, are larger than the slits 6. Situated immediately beneath the rib 8 is a rotary member 10, which is tubular at one end, as at 11, and is journaled at said end in a bearing 12 in the flange 5 of the burner. At 60 the other end said member 10 is provided with the neck 12^a, which extends through the flange 5 and is journaled therein, as shown. The end of the tubular portion 11 is open to the atmosphere, and standing in line therewith is a 65 jet-nozzle or valve 14, through which the vaporized fuel is delivered into the tubular member 11, from which it passes to the vapor-chamber 4.

15 designates a pipe leading to the source 70 of fuel-supply. Said pipe leads into a vaporizing-coil 17 and is controlled by a suitable valve 16, which is of peculiar construction, as will be presently described. The vaporizing-coil 17 stands directly over the burner-plate 75 and has a portion 18 thereof extending along over the burner-openings 9 in the rib 8. Said portion 18 extends to a coil 20, which coil is connected to the needlevalve or nozzle 14. Said coil 20 is preferably inclosed in a casing 21 80 and is constructed to be heated either by a suitable torch or by a burner 22, which gets its supply from the pipe 15 by means of a connection 23. This particular arrangement of vaporizing-coil and torch forms no part of my 85 present invention.

The valve 16 is what I call a "leaking-valve"—that is, it is so constructed that the supply of oil to the pipe 17 can never be entirely cut off. This result can be accomplished 90 by providing the valve with a very small groove 24, (see Fig. 7,) so that when the valve is closed onto its seat the liquid fuel can still leak past the same. The object of employing this kind of valve is to provide means for 95 maintaining a small pilot-flame which will keep steam up in the boiler when the automobile is at rest.

It will be obvious that when the supply of liquid fuel to the vaporizing-coil is reduced to 100

- a minimum by closing of the valve 16 the amount of vapor delivered to the vapor-chamber 4 will be also reduced to a minimum, and if said minimum quantity of vapor were allowed to distribute itself throughout the vapor-chamber 4 combustion would cease because of the excessive air which the vapor-chamber would contain. In order to avoid this, I have provided means whereby the closing of the valve 16 and the consequent cutting down of the supply of liquid fuel to a minimum is accompanied by the cutting out of a sufficient number of the burner-openings, so that combustion will be maintained. In this form of my invention this is accomplished by means of the rotary member 10, above referred to, which, it will be seen, is substantially semi-cylindrical throughout most of its length. The shape of the member 10 is such that when it is in a position shown in Figs. 2 and 4 it completely covers and closes the burner-openings 9, but when the position thereof is reversed it opens said burner-openings 9, but cuts off communication between the tube 11 and the vapor-chamber 4, thus practically reducing the size of the vapor-chamber to the interior dimensions of the member 10. The member 10, which is in the nature of a valve, is constructed to be operated simultaneously with the valve 16, the connections between said two valves being such that when the valve 16 is fully open the valve 10 is in the position shown in Figs. 2 and 4, while when said valve 16 is closed the valve 10 has been reversed. In this form of my invention I have provided the end of the stem 12 with a gear 26, meshing with a gear 27 on the stem 28 of the valve 16, so that the valve 10 is operated by the valve 16.
- When the burner is in use for generating steam, the valves 16 and 10 are opened, as shown in Figs. 2 and 4, and the liquid fuel on entering the vaporizing-coil becomes vaporized, and the vapor is thrown into and through the tube 11 and distributes itself throughout the vapor-chamber 4, as usual. The burner-openings 9 are closed, so that the vapor is ignited at each of the smaller burner-openings 6. Whenever it is desired to cut down the amount of heat generated and to generate only sufficient heat to keep the steam up in the boiler when no steam is being used—as, for instance, when the automobile is at rest—the valve 16 is closed, this operation reversing the position of the valve 10 and closing communication between the inlet-tube 11 and the vapor-chamber 4. At the same time the burner-openings 9 are uncovered. When the parts are in this position, a minimum amount of liquid fuel is delivered to the vaporizing-coil, where it becomes vaporized, and is then delivered to the reduced vapor-chamber formed by the member 10, from whence it passes to the burner-openings 9 and is ignited. There will be, therefore, a minimum number of burner-

openings at which combustion takes place, and the heat thus generated is just sufficient to keep the steam up in the boiler.

For the purpose of supplying sufficient air to the flame to get good combustion I place in the grooves of the corrugations in the burner-plate 3 air-supplying pipes 29, which have slits or jet-openings 30 therein, through which the air is delivered. These air-pipes are so placed that the jet-openings 30 stand below the burner-openings 6, whereby the jets of air are delivered upwardly toward the burner-openings. This I regard as quite important, because there is very much less danger of the flame being blown out by jets of air when thus delivered than when they are delivered either downwardly or horizontally. For supplying air to the pipes 10 I propose to employ the hood 33, which is illustrated as situated beneath the burner-chamber and as open at one end, as at 34, said open end when the burner is in use being directed forwardly or in the direction toward which the automobile is going. The back end 35 of said hood is shaped to partially inclose the flange 5, and the air-pipes 29 extend through the flange, and thus communicate at one end with the hood, as seen in Fig. 6. At the other end said pipes are preferably extended through the flange 5, as seen in Fig. 5, the pipes therefor being open to the air at both ends. The air is delivered through the jet-openings 30 partly by suction created by the upward movement of the products of combustion and partly by the forward movement of the vehicle and the consequent rush of air into the hood 33. From the above it will be seen that I have provided a burner in which the supply of liquid fuel to the vaporizing-coil and the number of burner-openings to which the vaporized fuel is delivered are controlled independently, but simultaneously, and while I have shown one way of accomplishing this I do not wish to be limited to the construction shown, as the details of the device may be varied without departing from the invention.

Having fully described my invention, what I claim as new, and desire to secure by Letters Patent, is—

1. In a burner, a burner-plate forming the top of a vapor-chamber and having a plurality of burner-openings, a vaporizing-coil above said burner-plate, a valve to control the supply of liquid fuel to the vaporizing-coil, means to determine the number of burner-openings to which the vaporized fuel is delivered, and connections between said means and the valve.

2. In a burner, a burner-plate having a plurality of burner-openings, a vaporizing-coil above said plate, a valve to control the supply of liquid fuel to the vaporizing-coil, means to control the number of burner-openings to which the vaporized fuel is delivered, and mechanical connections between said means and said valve.

3. In a burner, a burner-plate having a plurality of burner-openings, a vaporizing-coil above said plate, a valve controlling the supply of liquid fuel to the vaporizing-coil, and another valve controlling the number of burner-openings to which the vaporized fuel is delivered, and means connecting said valves for simultaneous operation.
4. In a burner, a burner-plate having a plurality of burner-openings, a vaporizing-coil, a valve controlling the supply of liquid fuel to the vaporizing-coil and constructed to give a minimum and a maximum flow in its two adjusted positions, means to control the number of burner-openings to which vaporized fuel is delivered, and connections between said means and the valve whereby the former is operated by the latter.
5. In a burner, a burner-plate having a plurality of burner-openings, a vaporizing-coil, a valve controlling the supply of liquid fuel to said coil, said valve being constructed to give a maximum and a minimum flow, and another valve operatively connected to the first-named valve and controlling the number of burner-openings to which the vaporized fuel is delivered, said latter valve when in one position shutting off the supply of vapor from a minimum number of burner-openings, and when in another position shutting off the supply of vapor from a maximum number of openings.
6. In a burner, a burner-plate having a plurality of burner-openings, a vaporizing-coil, a valve controlling the supply of liquid fuel to said coil, said valve being constructed to give a maximum and a minimum flow, another valve controlling the number of burner-openings to which the vaporized fuel is delivered, said valve when in one position shutting off the supply of vapor from a minimum number of burner-openings and when in another position shutting off the supply of vapor from a maximum number of burner-openings, and means to operate said valves simultaneously.
7. In a burner, a burner-plate having parallel corrugations, the ridges of said corrugations being provided with burner-openings, and air-supply pipes in the grooves between the ridges, said pipes having openings situated below the level of the burner-openings.
8. In a burner, a burner-plate having parallel corrugations, the ridges of said corrugations being provided with burner-openings, and air-supply pipes in the grooves between the ridges, said pipes having openings situated below the level of the burner-openings, and a hood beneath the burner and into which the air-supplying pipes open, the mouth of the hood opening at the front of the burner.
9. In a burner, a burner-plate forming the top of the vapor-chamber and having a plurality of burner-openings, a vaporizing-coil above the burner-plate, and mechanical means to control simultaneously the supply of liquid fuel to the vaporizing-coil and the number of burner-openings to which the vaporized fuel is delivered.
10. In a burner, a corrugated burner-plate, the ridges of said corrugations being provided with burner-openings, a valve device fitting the under side of one of said ridges and when in one position closing said openings, and when in another position opening them but preventing the passage of vaporized fuel to the other openings.
11. A burner, a corrugated burner-plate forming the top of the vapor-chamber, the ridges of the corrugations being provided with burner-openings, a valve device beneath one of said ridges and through which the vaporized fuel is admitted to the vapor-chamber, and means to turn said valve whereby the number of burner-openings to which the vaporized fuel is delivered may be regulated.
12. In a burner, a corrugated burner-plate forming the top of the vapor-chamber, the ridges of the corrugations being provided with burner-openings, a vaporizing-coil above the burner-plate, a valve device beneath one of the ridges of said plate through which valve device the vaporized fuel is admitted to the vapor-chamber, a supply-valve controlling the supply of liquid fuel to the vaporizing-coil, and operative connections between said supply-valve and valve device.
13. In a burner, a burner-plate having a plurality of burner-openings, a vaporizing-coil above said plate, a valve controlling the supply of liquid fuel to the vaporizing-coil, another valve determining the number of burner-openings to which the vaporized fuel is delivered, and mechanical means connecting said valves for simultaneous operation.
- In testimony whereof I have signed my name to this specification in the presence of two subscribing witnesses.
